A. H. BLACKBURN AND F. E. FLEMING.
UNDERFEED FURNACE.
APPLICATION FILED MAR. 22, 1919.

1,326,906.

Patented Jan. 6, 1920.

UNITED STATES PATENT OFFICE.

ARTHUR H. BLACKBURN, OF DOWNEES GROVE, AND FRANK E. FLEMING, OF CHICAGO, ILLINOIS, ASSIGNORS TO THE UNDERFEED STOKER COMPANY OF AMERICA, OF CHICAGO, ILLINOIS, A CORPORATION OF NEW JERSEY.

UNDERFEED FURNACE.

1,326,906.

Specification of Letters Patent. Patented Jan. 6, 1920.

Application filed March 22, 1919. Serial No. 284,396.

To all whom it may concern:

Be it known that we, ARTHUR H. BLACKBURN, a subject of the King of Great Britain, residing at Downers Grove, in the county of DuPage and State of Illinois, and FRANK E. FLEMING, a citizen of the United States, residing at Chicago, in the county of Cook and State of Illinois, have invented certain new and useful Improvements in 10 Underfeed Furnaces, of which the following is a specification.

Our invention relates to underfeed furnaces and has for its general object to provide a novel and advantageous self-cleaning 15 side-floor construction by which ash may be fed from adjacent a central retort to appropriate ash-removal mechanism located along the side-wall of the furnace. It consists in the features of construction and combinations and arrangements of parts herein- 20 after more fully described and set forth in the claims.

In the drawings Figure 1 is a fragmentary plan view of a furnace embodying our invention, and Fig. 2 is a transverse vertical section.

In the drawings 10 indicates a retort (or the side retort of a battery) into and along which fuel may be fed in accordance with 25 practice customary in underfeed furnaces, and 11 indicates generally a side-floor structure. This floor, with the retort, separates the usual wind-box 12 from the combustion space 13, the flooring extending to a longitudinal 30 partition or beam 14 which separates the wind-box laterally from an ash pit 15 close to the side wall 16. A dump door 17, mounted on a rock shaft 18, which extends through the front wall 19 for operation 35 by a handle 20, illustrates a suitable ash-disposal means arranged adjacent to, and extending along, the side wall, but other forms of ash disposal devices may be employed in lieu thereof.

To complete the frame on which the movable parts of the floor structure may find appropriate support, cross-bars 21 may be extended from the partition beam or casting 40 14 to the retort 10. Suitable ribbing, for strength and to afford bearings, is provided on the frame parts, together with pivot lugs or ears 22 and 22' in which are mounted the shafts 23 and 23' which extend longitudinally, in parallelism, to support

the oppositely-pivoted floor sections 24 and 25. These sections, thus pivoted adjacent their opposite edges, have their proximate or meeting edges connected with operating means for raising and lowering them so that the floor may be "shaken," or moved to feed ash laterally toward the dump door 17. Specifically, the outer floor section 24 has its floor plate 26 constituting a supporting surface normally sloped upwardly from its outer edge, its bottom rib being connected near its inner edge with a pin 27 which is carried by a vertical link 28, this link being operated from crank 29 on rock-shaft 30 which extends through the front wall and is provided with a handle 31. The opposing section 25 has its floor plate or supporting surface 32 slightly overlapping its fellow, and preferably slightly separated therefrom to leave an air opening 33, and to permit the desired movements between the plates its bottom rib is cut away as at 34 and is slotted as at 35 to engage the pin 27. Preferably this floor section has a convexly curved skirt 36 substantially fitting against the corresponding concave curve of the retort side, and it also has, preferably, a wall portion 37 forming an inclined lip for the retort, when in normal position, and provided with twyers 38.

The arrangement described permits the floor-joint to be either raised or lowered, and to hold the parts normally in position as shown, a pivoted latch 40 for handle 31 may be employed. The stated correlation of the floor plate parts gives an advantageous feeding action to the floor, enabling the fuel and ash to be handled with desirable facility and enabling the spread of the burning fuel to be nicely regulated. Shaking the floor between its mid position shown and lowest position of link 28 will cause the slope of the inner course or section to increase so that fuel will be fed outwardly from adjacent the retort and tend to lodge on the outer section. Shaking of the floor between its mid position and upper limit tends to evacuate the outer section of its ash-load and only resultantly to affect the load on the inner section, the slope of which is decreased by the action. Rocking above and below center of course intensifies the cleaning and feeding action.

Of course as the connected floor sections

are moved to vary their relative angles, any clinker formations tend to be broken up, and the rocking of the twyer-block-portion tends to prevent or overcome the formation of clinkers adjacent the lip of the retort.

We have spoken of the sections as though they were integral plates of full retort length, but they may conveniently be made 10 as shown, in shorter lengths, and jointly operated in unison, this being a structural detail advantageous from the standpoints of ease of manufacture and repair.

While we have herein described in some 15 detail a particular embodiment of our invention, it will be apparent that many changes in the specific construction may be made without departure from the spirit and scope of the same, within the scope of the 20 appended claims.

What we claim is:

1. In an underfeed furnace, the combination with a retort, and ash-disposal means laterally spaced from said retort, of an intervening side-floor structure comprising plates respectively pivoted adjacent each the retort and the ash disposal means, and means for raising and lowering the proximate free edges of said plates.
- 30 2. In an underfeed furnace, the combination with the retort and ash disposal means laterally spaced from said retort, of an intervening laterally down-sloping floor structure comprising inner and outer courses of short plates, respectively pivoted adjacent 35 their opposite edges and overlapping at their adjacent edges, and means for raising and lowering, jointly, the meeting edges of the plates.
- 40 3. In an underfeed furnace, the combination with the retort and ash disposal means laterally spaced from said retort, of an inner floor-section pivoted adjacent the retort and providing a supporting surface and a skirt, said skirt shaped to maintain substantial approximation of contact with the retort as the section is rocked, a second floor-section pivoted adjacent the ash disposal means and extending inward to an approxi-

mation of contact with the free edge of the first said section, and means for raising and lowering the adjoining edges of said sections in unison.

4. In an underfeed furnace, the combination of a retort, ash disposal means laterally spaced from said retort, an inner floor section pivotally mounted adjacent said retort and comprising a supporting surface and a skirt, said supporting surface extending laterally outward beyond the pivot and said skirt extending inwardly therefrom, said skirt comprising an inclined portion with twyers therein forming an air supplying lip for the retort and a curved portion to maintain an approximation of contact with the retort as the section is moved, an outer floor section pivotally supported adjacent the ash disposal means and having a supporting surface extending inwardly therefrom to an approximation of contact with the free edge of the first said section, and means for raising and lowering the adjacent edges of said sections jointly.

5. In a furnace of the character described, 75 the combination of a retort, a partition structure having pivot lugs near its top and spaced from said retort, cross-bars connecting said partition structure and the retort and having pivot lugs adjacent the retort, 80 floor plate members pivotally carried by said spaced lugs and having their free edges overlapped, a rock shaft, and connections from said rock shaft to the free ends of both said plate structures to raise and lower them 85 jointly.

6. In a furnace of the character described, 90 a side wall, a retort, an intervening partition, ash dump means between the wall and partition, and self-cleaning floor sections between the partition and retort, such sections pivoted near their opposite edges, operating means for raising and lowering the adjoining edges of said sections and means for holding said operating means in mid-position.

ARTHUR H. BLACKBURN.
FRANK E. FLEMING.
